UNITED STATES PATENT OFFICE

ADAM WEBER AND IGNATZ HERZOG, OF NEW YORK, N. Y., AND AUGUST T. SCHUESSLER, OF NEWARK, NEW JERSEY.

IMPROVEMENT IN APPARATUS FOR THE MANUFACTURE OF GAS.

Specification forming part of Letters Patent No. 175,536, dated March 28, 1876; application filed January 28, 1876.

To all whom it may concern:

Be it known that we, ADAM WEBER and IGNATZ HERZOG, both of the city, county, and State of New York, and AUGUST TH. SCHUESSLER, of Newark, in the county of Essex and State of New Jersey, have invented a new and useful Improvement in Apparatus for the Manufacture of Gas for illuminating and heating purposes, which improvement is fully set forth in the following specification, reference being had to the accompany drawings in which—

Figure 1 represents a vertical section of the apparatus used in carrying out this invention, the line $x x'$, Fig. 2, indicating the plane of the section. Fig. 2 is a horizontal section of the same in the plane $y y'$, Fig. 1. Fig. 3 is a vertical section in the plane $z z'$, Fig. 2. Fig. 4 is a plan or top view. Fig. 5 is a vertical section in the plane $x' x'$, Fig. 2. Fig. 6 is a side view.

Similar letters indicate corresponding parts.

This invention relates to certain improvements in apparatus for the manufacture of gas by the decomposition of steam and liquid hydrocarbons, its object being to provide for the superheating of the steam, and the decomposition of the same and the liquid hydrocarbons in a more thorough and economical manner than has heretofore been accomplished.

Our invention consists, first, in the combination, with said longitudinal superheaters, and a series or bench of two or more vertical retorts, located at one or both sides of the furnace, of a series of vertical heaters located on the outside of each series of vertical retorts, and communicating with the same, as hereinafter more fully set forth; second, in the combination of the longitudinal and vertical superheaters with a series of two or more vertical retorts, provided with superheating-chambers in their walls communicating with the vertical superheaters and with the interior of said vertical retorts, as hereinafter more fully set forth; third, in combination with each pair of the vertical steam-decomposing retorts, of branch pipes leading to an intermediate pipe, and two or more vertical oil-decomposing retorts communicating with said intermediate pipe by similar branch

pipes, as more fully hereinafter set forth; fourth, in combination with the vertical retorts, an intermediate pipe communicating with said retorts and the hydraulic main, and provided with a partition below the branch pipes which form the exit from the oil-decomposing retorts, as more fully hereinafter set forth.

In the apparatus shown in the drawings, six pairs of retorts are shown, three on each side of the fire-place, and in this figure the letter A designates the fire-place, which occupies the middle of the furnace A', in which are placed the steam-decomposing retorts B B' C C', and the hydrocarbon-retorts D D'. On each side of the fire-place is a brick wall, E, which is perforated with a number of apertures, a a, through which the flames can freely circulate. In each of the brick walls E are two return-channels, b c, one above and the other below the apertures a, and one branch of each of the return-channels communicates with a steam-supply pipe, F, while the other branches of said return-channels connect, by means of pipes G, with the upper parts of the steam-decomposing retorts B and C.

All the retorts in the furnace A' are placed in a vertical position, and they are retained in the proper positions by partition-walls d, each of which is provided with a return-channel, e, one branch of which connects with the steam-supply pipe F, while the other branch connects with one of the steam-decomposing retorts B or C.

In the bodies of the steam-decomposing retorts B B' C C', next to the fire-place, are return-channels f, one branch of each of which connects with the steam-supply pipe F, while the other branch thereof communicates with one of the retorts B or C.

As the steam circulates through the return-channels b, c, e, and f it becomes superheated, and in this state it enters the retorts B C. By the action of the steam the bricks which form the walls E on the sides of the fire-place, and the partition-walls d, are cooled off and preserved against the destructive action of the fire, and, by passing steam through the return-channels f in the bodies of the retorts, those portions of said retorts which are exposed to the greatest

heat are partially cooled, and the heat which acts on the bodies of the retorts is equalized, so that the same are less liable to crack than they are if exposed to a greater heat from one side than from the other.

All the retorts B B', C C', and D D' are open at their bottoms, and they are placed over flues *g h i*, which are so formed that the flues *g* form connections between the retorts B B', while the flues *h* connect the retorts C C', and the flues *i* the retorts D D'. (See Fig. 5.) If the furnace A' is built on columns H, as shown in Fig. 1, the flues *g h i* are provided with openings *j*, which openings can be closed below by suitable covers, and through which, when the covers are removed, the ashes and the spent contents of the retorts can be removed. If the furnace is built on the ground, the flues *g h i* communicate with the lateral flues *k*, which can be closed by suitable doors, and through which, when the doors are open, the ashes and spent contents of the retorts can be removed.

The retorts B B' C C' are filled with coke, coal, or other carbon, and they are provided at their bottoms with grates *l*, formed of bricks, so that the coals or coke cannot drop out while the ashes formed in the retorts can be raked out, and at the same time the communication between said retorts and the flues *g* is not stopped. The retorts D D' may also be provided with similar grates at their bottom ends, or with any other device suitable for the purpose.

In the example shown in the drawing, two perforated bricks, *m*, are placed transversely across the bottoms of the retorts D D', and on said transverse bricks is placed a longitudinal brick, *n*. These retorts are filled with pumice-stone or other incandescent porous material, and after they are closed at the top hydrocarbons are introduced in a liquid or vaporous form.

On the top of the furnace A' is situated a pipe, I, which is closed at one end, and connects at its opposite end with the hydraulic main J. From this pipe extend branch pipes K L M N, which connect, respectively, with the retorts B', C', D, and D', the branch pipes M and N being cut off from each other by a partition, o, so that the gases which pass from the retorts B' and C' into the pipe I are compelled to enter the retort D, pass down through this retort and up through the retort D', before they can escape into the hydraulic main.

After the retorts B B' and C C' have been charged with coal or coke and the retorts D D' with pumice stone or other incandescent porous material, the covers of all the retorts are firmly closed and the fire in the furnace is started. When the retorts have become heated to the desired temperature the steam-supply pipe is opened and steam is permitted to pass through one or more of the superheaters *b*, *c*, *e*, and *f*, all said superheaters being employed by preference, so that the parts containing them are protected against the de-

structive influence of the fire. The steam passes down through the retorts B and C, and up through the retorts B' C', and in its passage through the incandescent coals contained in said retorts it becomes decomposed, and the gases resulting from this decomposition pass down through the retorts D and up through the retorts D', where the same come in contact with the hydrocarbon, which is admitted in a liquid or vaporous form into said retorts, as above stated. By the action of the porous material contained in said retorts the hydrocarbon vapors are distributed over a large surface, and they readily combine with the gases resulting from the decomposition of the superheated steam, and thereby a fixed gas is produced, which can be used for illuminating or heating purposes.

By using two or more benches of retorts the operation can be made continuous, since each pair of steam-decomposing retorts and each pair of carbonizing-retorts can be shut off and cleaned out and recharged without stopping the operation. In practice the steam-pipes and other exposed parts will be covered by asbestos or other suitable material to prevent undue radiation and waste of heat.

Another advantage of our apparatus is that an abundance of superheaters are provided, so that if one of the superheaters should give out it can be thrown out of action without disturbing the operation of the apparatus, and furthermore, the steam can be employed at a low pressure, and comparatively small quantities of steam have to be passed through each superheater, so that all the steam becomes thoroughly superheated before it enters the decomposing-retorts.

The retorts B B', C C', and D D' are provided with intermediate braces, so that they support each other, while the flames can circulate all round the same. By connecting the several retorts and the hydraulic main by means of a common dip a uniform product is obtained from our apparatus.

As thus constructed it will be perceived that the steam can be generated and superheated in the same furnace and by the same fire employed for the generation of the gas, and by reason of the flues formed by the superheaters and the retorts as arranged the steam is compelled to take a tortuous course throughout the furnace by which it is most thoroughly heated, and is brought to a state fit for immediate decomposition by the time it reaches the first series or bench of retorts. In these retorts it is thoroughly decomposed, and the resultant gas is passed on to the oil-decomposing retorts, the gages being finally discharged through the branch pipes and central pipe into the hydraulic main or the holder, or otherwise carried off for consumption. It will be perceived that the steam-decomposing retorts are arranged in pairs, which can be operated wholly independent of each other, by which we are enabled to decrease or increase the amount of gases

generated by the decomposition of the water, as occasion requires; and, further, that the gases generated by the decomposition of the water can be employed alone, without being enriched by the oil-gas, when the gas is required for heating purposes simply.

What we claim as new, and desire to secure by Letters Patent, is—

1. In combination with the longitudinal superheaters, the vertical superheaters and steam-decomposing retorts located and connected together, substantially as described.

2. The combination of the longitudinal and vertical superheaters with the vertical steam-decomposing retorts, provided with superheating-passages in their walls communicating with the vertical superheaters and the interior of said retorts, substantially as described.

3. In combination with each pair of vertical steam-decomposing retorts, the branch pipes,

having valves, the central pipe I, and the vertical oil-decomposing retorts, the whole connected together and communicating with each other, substantially as described.

4. The combination, with the vertical retorts, of an intermediate pipe communicating with said retorts and the hydraulic main, and provided with a partition below the branch pipes, which form the exit from the decomposing-retorts, substantially as described.

In testimony that we claim the foregoing we have hereunto set our hands this 24th day of January, 1876.

ADAM WEBER.

I. HERZOG.
